(57) **CLAIM**

The ornamental design for a charger for an electronic cigarette, as shown and described.

DESCRIPTION

FIG. 1 is a front perspective view of our charger for an electronic cigarette;

FIG. 2 is a rear elevational view thereof;

FIG. 3 is a front elevational view thereof;

FIG. 4 is an elevational view of the right side thereof;

FIG. 5 is an elevational view of the left side thereof;

FIG. 6 is a top plan view;

FIG. 7 is a bottom plan view;

FIG. 8 is a rear perspective view thereof;

FIG. 9 is a front perspective view showing environmental structure in broken lines; and,

FIG. 10 is a rear perspective view showing environmental structure in broken lines.

The broken lines depicted in the drawings are directed to environment and are for illustrative purposes only and form no part of the claimed design.
